UNITED STATES PATENT OFFICE

2,680,018

SHEET METAL FEEDER

William A. Fletcher, Daleville, Ind., assignor to
 General Motors Corporation, Detroit, Mich., a
 corporation of Delaware

Application August 23, 1951, Serial No. 243,208

5 Claims. (Cl. 271—2.5)

1

This invention relates to apparatus for feeding sheet metal between dies of a punch press and, more particularly, to the type of feeder shown in my copending application, S. N. 125,223 filed November 3, 1949, now U. S. Patent No. 2,676,799, issued April 27, 1954, and comprising a horizontally movable feeder carriage which supports a fixed, sheet metal engaging jaw and a vertically movable jaw for clamping the sheet metal against the fixed jaw prior to movement of the carriage to move the sheet metal. A mechanism causes vertical movement of the movable jaw to grip the sheet, horizontal movement of the carriage to move the sheet, vertical movement of the movable jaw in the opposite sense to release the sheet metal and horizontal movement of the carriage in the opposite sense to a starting position. If two feeders are required, respectively, to push the sheet metal into the press and to pull it out of the press, two of such mechanisms operating in synchronism are provided.

An object of the present invention is to provide two sheet metal feeding devices, respectively, for pushing in and pulling out the sheet metal with respect to a punch press, each of said devices having sheet metal gripping jaws and both operated by a single mechanism of the type above referred to. In the disclosed embodiment of the invention, this object is accomplished by the use of a parallelogram of articulated members two of which are parallel to the direction of movement of the sheet metal and two of which extend transversely of said direction of movement. The single mechanism swings the parallelogram for the purpose of gripping and releasing the sheet metal by the two feeding devices and moves the parallelogram bodily for the purpose of moving the sheet metal and returning the feeding devices to a starting position.

Further objects and advantages of the present invention will be apparent from the following description, reference being had to the accompanying drawings wherein a preferred embodiment of the present invention is clearly shown.

In the drawings:

Fig. 1 is a side view in the direction of arrow 1 of Fig. 2 of a punch press equipped with a sheet metal feeder embodying the present invention.

Fig. 2 is a view in the direction of arrow 2 of Fig. 1.

Fig. 3 is a fragmentary view on a larger scale in the direction of arrow 3 of Fig. 2.

Fig. 4 is a fragmentary view in the direction of arrow 4 of Fig. 3.

Fig. 5 is a sectional view on line 5—5 of Fig. 3.

Figs. 6 and 7 are fragmentary, sectional views on lines 6—6 and 7—7 of Fig. 2.

2

Fig. 8 is a sectional view on line 8—8 of Fig. 6. Fig. 9 is a sectional view on line 9—9 of Fig. 7.

Figs. 10, 11 and 12 are sectional views, respectively, on lines 10—10, 11—11 and 12—12 of Fig. 5.

Fig. 13 is a sectional view on line 13—13 of Fig. 2.

Fig. 14 is a sectional view substantially on line 14—14 of Fig. 1.

10 The punch press, with which the feeding device is associated, is, for example, that shown in the copending application of C. A. Nichols et al. Serial No. 246,363, filed September 13, 1951. It comprises a base 20 supported by legs 21 and supporting a frame 22 which supports a head 23. The parts 20, 22 and 23 are clamped together by rods 24 (Fig. 2) which receive nuts 25 (Fig. 1) by which the parts are secured. Frame 22 supports bracket 26 whereupon a motor 27 is mounted which through belt 29, drives a flywheel 30 which drives a shaft 31 (Figs. 1 and 2) which operates a crank (not shown), which reciprocates a ram 32 carrying a punch assembly 33 which cooperates with a die assembly 34 attached to a plate 35 supported by base 20.

20 Shaft 31 drives a sprocket 36 connected by chain 37 with a sprocket 38 which is shown in Fig. 13, and is connected with a shaft 39 journaled in bearings 40 supported by sleeves 41 attached to a bracket 42 attached to a bracket 43 attached to frame 22. Shaft 39 provides an eccentric 45 connected by pitman 46 (Figs. 1 and 2) connected with a ram 48 guided for vertical movement by bracket 42 and retained by plates 49. A brace 46a (Fig. 1) attached to bracket 42 reinforces this bracket and provides clearance for the pitman. The ram 48 carries a blade 50 cooperating with a blade 51 for shearing the scrap sheet metal from which punchings have been cut by the members 33 and 35. The blade 51 is secured to housing 80 (Fig. 6) by a plate 51a attached to housing 80 by screws 51b.

30 Shaft 39 (Fig. 13) drives a sprocket 60. Referring to Fig. 2, sprocket 60 is connected by one chain 61 with a sprocket 62. Referring to Fig. 5, sprocket 62 is journaled on bearings 63 supported by a shaft 64. Sprocket 62 provides a notch 65 for receiving a clutch dog 66 which is received by a slot 67 in a clutch disc 68 drivingly connected with shaft 64 by a key 69. A spring 70 urges the dog 66 toward the sprocket 62 which provides the driving clutch member. The spring 70 is retained by a plate 71 attached to a clutch disc 68. Disc 68 and plate 71 are retained by nuts 72 which, when tightened, force the disc 68 against a shoulder 73 of shaft 64.

Screws 74 secure a brake drum 75 to disc 68. Drum 75 is engageable by a brake lining 76 attached to brake shoes 77 and 78. As shown in Fig. 3, shoes 77 and 78 are connected by a pin 79 and shoe 77 is fixed by a screw 81 to a rod 82 (Fig. 4) supported by a bracket 80 as shown in Fig. 4. Shoe 77 (Fig. 3) is fixed to a rod 83 which extends through a hole 84 provided by shoe 78 and which is connected with a piston in cylinder 85 supported by shoe 78. While the machine is running, the brake lining engages the drum with substantially no pressure, pressure fluid having been admitted to the left end (Fig. 3) of cylinder 85. When the machine is stopped, pressure fluid is admitted to the right end of cylinder 85 to cause braking pressure to be applied to the brake drum to hold it in a fixed position so that the feeding mechanism, driven by shaft 64, will not coast.

Bracket 80 supports a bracket 90 which supports a cylinder 91 containing a piston connected with a rod 92 providing a slot 93 for receiving a pin 94 by which the rod 92 is connected with a lever 95 pivoted at 96 on bracket 90. Lever 95 provides a blade 97 which, in the position shown, can be received by a space 98 (Fig. 5) between the shoulder 99 of the dog 66 and the brake drum 75 whereby rotation of the dog about the axis of shaft 64 causes it to be retracted from the sprocket 62, thereby disconnecting the latter from the clutch disc 68. Fig. 3 shows the blade 97 in position to engage the dog 66. When the machine is operating, pressure fluid is admitted to the left end (Fig. 3) of cylinder 91 to cause the blade 97 of lever 95 to move counterclockwise away from the path of movement of the dog 66. When stopping of the feeding mechanism is desired, pressure fluid is admitted to the right end of cylinder 91 to effect clutch disengagement as described and concurrently pressure fluid is admitted to the right end of cylinder 85 to effect application of the brake as shown in Fig. 3. Therefore, the feeding mechanism is disengaged from a power source provided by the punch press and the brake is applied so that the feeding mechanism will not coast.

The cycle of operation of the feeding mechanism occurs once during each cycle of operation of the punch press. Therefore, the shafts 31 and 39 (Fig. 1) are geared one to one and shafts 38 and 64 are geared one to one. The slack in chain 61 (Fig. 3) is taken up by a sprocket 100 which meshes with the chain 61 and which is pivotally supported by a stub shaft 101 supported by a plate 102 guided for movement by ways 103 provided by bracket 80. Plate 102 is adjusted by turning nuts 104 threaded on a screw 105 which extends through a hole in a boss 106 of bracket 80. Plate 102 is also fixed in position by screws 107 passing thru slots 108 and threaded into bracket 80.

As shown in Figs. 1 and 3, bracket 80 is secured to a plate 110 welded to base 20 and forming a part of a leg 21. A key 111 locates the bracket 80 relative to the plate 110 and screws 112 secure these parts together. At the right side of the punch press as shown in Fig. 1, there is a plate 110' welded to base 20 and forming a part of the right leg structure 21. A key 111' locates a bracket 80' with respect to plate 110' and screws 112' secure these parts together. As shown in Figs. 5 and 6, bracket 80 provides bearing bushings 115 which receive two horizontally movable rods 116 which, as shown in Fig. 7, is supported for horizontal movement also by the

bracket 80' which provides a portion 117 supporting bearing bushings 118 (Fig. 9).

Rods 116 (Fig. 6) support a carriage 120 fixed to the rods 116 by pins 121 (Fig. 8). Referring to Fig. 7, a carriage 122 is fixed in a similar manner to rods 116. The rods 116 and the carriages 120 and 122 provide, in effect, a horizontal side of a parallelogram which includes a transverse link 123 (Fig. 6) and a transverse link 124 (Fig. 7) pivotally connected with carriages 120 and 122, respectively, by rod 125 (Fig. 6) and rod 126 (Fig. 7), respectively, received by bushings 125a and 126a, respectively. The transverse links 123 and 124 support a horizontal link which includes two rods 127 (Fig. 8), the ends of which are fixed by nuts 129 (Figs. 6 and 7) to sleeves 130. There are four sleeves 130, each of which has a lug 131 keyed to a shaft 132 which extends through bushings 133. Two of the bushings 133 are carried by the link 123 (Fig. 8) and two of the bushings by link 124. The carriages 120 and 122 and the links 123 and 124 are preferably made of light-weight metal such as aluminum.

Each carriage 120, 122 (Figs. 6 and 7) provides a yoke 140 (Fig. 8). Yoke 140 supports a fixed clamping jaw 142 secured by screws 143. Fixed jaw 142 cooperates with a movable jaw 144 which is shown in Fig. 6 in sheet metal clamping position. The sheet metal engaging portions or tips of the jaws are made of hard metal such as "chromalloy" or "stellite." When permitted to do so, jaw 144 is retracted from jaw 142 by spring 145 which urges jaw 144 downwardly until it is received by flanges 146 of bars 147 which screws 148 attach to a bar 149 which screws 149a attach to the carriage. Each of the movable jaws 144 is connected by a pin 150 with a rod 151 providing a ball 152 received by a spherical socket 153 of a spring pressure pad 154 guided by a bushing 155 of link 123 or 124. Each of the links 123, 124 provides a recess 156 for receiving a compression spring 157 confined between the pad 154 and a pad 158 forming the head of a screw 159 threaded through a bushing 160 which screws 161 attach to the link. The initial compression of spring 157 can be adjusted by turning the screw 159 after a lock nut 162 has been loosened.

The link 123 provides an arm 165 which receives a ball bearing 166, the outer race and the inner race of which are journaled on a crank pin 167 which, by mechanism to be described, is caused to move in a path 168 which is substantially a square having rounded corners. Direction of movement of the axis of pin 167 is indicated by the arrows 169. When the axis of pin 167 was at location S on path 168, the links 123 and 124 would have been swung clockwise about rods 125 and 126, respectively, from the position shown in Figs. 6 and 7, respectively. Under these conditions, the distance between pads 154 and movable jaws 144 would be greater. Therefore, springs 157 would have expanded until the flanges 154f of the pads 154 had engaged the lower ends of the bushings 155, and no force from springs 157 would have been transmitted to rods 151. Therefore, springs 145 would have been released to push the jaws 144 downwardly to place them in non-gripping positions. As the axis of pin 167 moves upwardly to point G, then distance between the movable grippers 144 and rods 154 decreases so that the springs 157 are compressed, thereby overcoming the spring 145 and causing the movable jaws 144 to move upwardly to clamp the sheet metal between them.

and the fixed jaws 142. During movement of the axis of pin 167 around the upper left-hand corner of path 168, the pin has movement vertically upwardly to increase the gripping action and movement horizontally. Thus, the axis of the pin moves horizontally. As the pin moves around the upper right-hand corner of path 168, it has movement horizontally and vertically downwardly. During the horizontal movement of pin 167, the parallelogram is moved bodily to the right in Figs. 6 and 7 to move the sheet metal. Feeding movement ceases when the axis of pin 167 arrives at the vertical right-hand side of path 168 and the sheet metal is ungripped or released when the axis of pin 167 arrives at point UG because at this time swinging of the links clockwise has begun. During further movement down the right-hand vertical side of path 168 the swinging of the links clockwise continues; and, as the axis of pin 167 moves around the lower right-hand corner of path 168 along the lower horizontal portion and then to the point S, the parallelogram is moved bodily to cause the feeding devices to return to starting position with the sheet metal grippers still separated.

The plate 170 shown at the left in Fig. 7 and at the right in Fig. 14 supports the sheet metal as it passes to the dies 34. Plate 170 has a depressed surface 170a which receives plates 171 upon which the sheet metal moves. Plates 171 are secured to side flanges 172 of a bracket 173 which screws 174 attach to the yoke 140 in Fig. 7. Plates 171 provide a sliding cover for the hole 175 in plate 170 through which the yoke 140 extends. The plate 176 shown at the left in Fig. 14 and in Fig. 6 has a hole 175' covered by sliding plates 171' which perform the same functions as plates 171 in Fig. 7.

During the return of the feeder carriages to starting position, a back movement of the sheet metal is prevented, after the sheet metal has been fed part-way through the press, by the cooperation of certain pins provided by the punch assembly with certain punched holes in the sheet metal. It will be noted that the engagement of the punch assembly with the die assembly can take place during that portion of the travel of the axis of pin 167 between the points UG and G on path 168, which is about two-thirds of a revolution of the press operating shaft. When starting a new strip into the press, it is necessary to prevent back movement of the sheet metal until it has arrived at a station in the press wherein press operated pins are received by holes in the sheet metal. As shown in Figs. 7 and 9, there are rolls 180 and 181 between which the sheet metal passes. Roll 180 receives press-fitted spherical journals 182 received by spherical, split-bearing bushings 183 received by the eyes 184 of rods 185 vertically movable in bushings 186 and attached to a bar 187 attached to a rod 188 attached to a piston in a cylinder 189 supported by bracket 80'. When pressure fluid is admitted to the upper end of cylinder 189, the rods 185 are forced downwardly with pressure sufficient to cause such frictional resistance to rotation of roll 180 as will prevent rotation of roll 180 by tendency of the sheet metal to move backward as the feeder carriages return to starting position. After the sheet metal has arrived at a station in the punch press where press operated pins are received by holes in the sheet metal, the application of pressure fluid to the upper end of cylinder 189 has been cut off and

exhausted so that roll 180 is held down against the sheet metal merely by gravity.

The mechanism for causing the axis of pin 167 to move in path 168 will now be described with reference to Figs. 5, 10, 11 and 12. Referring to Fig. 5, shaft 64 is supported by taper roller bearings 190 retained in bracket 80 by a disc 191 secured by screws 192. Nuts 193 threaded on shaft 64 clamp the inner races of bearings 190 against the shoulder 194 of shaft 64. Shaft 64 is integral with a portion 195 of larger diameter and a portion 196, called a drum, of still larger diameter. The drum portion 196 is supported by roller bearings 197 located in a cage 198 retained in a recess of bracket 80 by the flange 199 of drum 196. Drum 196 carries ball bearings 200 for rotatably supporting a shaft 201 providing a pinion 202 meshing with a fixed ring gear 203 which screws 204 attach to bracket 80. Shaft 201 provides the crank pin 167, the axis of which is eccentric to the axis of shaft 201. As stated before, the pin 167 receives bearings 166 carried by the arm portion 165 of link 123. As shown in Fig. 12, the pinion 202 which meshes with ring gear 203 has a diameter equal to one-fourth the diameter of the ring gear. The axis 201a of shaft 201 is shown vertically above the axis 64a of shaft 64. In Fig. 11, the axis 201a of shaft 201 is shown vertically above the axis 64a of shaft 64 which includes the drum 196. In Fig. 10, the axis 201a of shaft 201, the axis 64a of shaft 64 and the axis 167a of crank pin 167 are in vertical alignment. In consequence of this relationship and when the distance between axes 201a and 167a is approximately .36 of the radius of the pinion 202, during one rotation of shaft 64, the axis 167a of crank pin 167 will move in path 168 which is approximately a square with rounded corners; and two opposite sides of the square path are parallel to the path of movement of the sheet metal. As disclosed in my copending application, the path 168 is one form of a prolate hypotrochoid. Path 168 is such that the sheet metal is not jerked when it is started and when it is stopped because its movement is gradually accelerated and gradually decelerated. Furthermore, the time of feeding is only about one-third of a revolution of shaft 64 and of the punch press shaft 31 and two thirds of a revolution is available for lowering and raising the punch.

As disclosed in the application of Nichols et al. referred to, in the case of a punch press which produces three armature core laminations at each stroke, three feeding steps are required to move the sheet metal from the punches and dies when holes are punched out preparatory to forming armature core lamination blanks to the punches and dies when the laminations are punched from the sheet metal.

While the embodiment of the present invention as herein disclosed constitutes a preferred form, it is to be understood that other forms might be adopted.

What is claimed is as follows:

1. A sheet material feeding apparatus for intermittently feeding material into and out of a machine comprising two brackets attached to a machine, at the material entrance side and exit side thereof, and articulated link members forming a parallelogram, said link members including; parallel rods supported and guided by the brackets for movement parallel to the material, longitudinally spaced gripping frames attached to the rods, transverse links pivotally carried by the gripping frames, link members parallel to the

rods, pivotally supported by and connecting the transverse links, a pair of jaws carried by each gripping frame including a fixed jaw adjacent one side of the material, and a movable jaw adjacent the other side of the material supported by the gripping frame for limited retraction from the fixed jaw, means for effecting retraction of the movable jaw in a path at right angles to the sheet metal, means connecting each transverse link to the movable jaw to effect a gripping action of the material, and timing means connected to at least one transverse link for pivotally swinging said link and for bodily moving said link in the direction of feeding of the material and for bodily moving said link in a direction opposite to the feeding direction thereby intermittently applying a closing force to the movable jaws while bodily moving the parallelogram in the direction of movement of the material and permitting release of the jaws while bodily moving the parallelogram in an opposite direction.

2. Apparatus as defined in claim 1 in which the connecting means associated with each movable jaw includes, in tandem relation, a fixed pressure pad, a helical compression spring, a movable pressure pad all supported by a transverse link and a rod for transmitting motion from the movable pressure pad to the movable jaw, all of said parts being substantially in alignment when the pivot center line of the transverse link is at right angles to the link members, and means limiting motion of the movable pad away from the fixed pad during movement of the transverse link in a direction opposite to the feeding movement.

3. The apparatus as set forth in claim 1 having a timing means in combination comprising; a mechanism shaft adapted to be connected with a press shaft so as to rotate at the same speed therewith, a fixed internal gear concentric with the mechanism shaft, a pinion having a pitch radius of one fourth the pitch radius of the ring gear supported by the shaft for orbital movement about the axis thereof while meshing with the ring gear, a crank carried by the pinion and having its axis parallel to the pinion axis spaced from it a distance of about .36 the radius of the pinion whereby, during a revolution of the press shaft, the axis of the crank describes a prolate hypotrochoid figure which is substantially a square with rounded corners, and means for connecting the crank with said transverse link.

4. A material feeding apparatus adapted for use with a punch press comprising: articulated link members forming a parallelogram adapted to reciprocally move in the direction of movement of material; said parallelogram including; axially movable parallel rods, at least two gripping frame members each axially spaced and transversely attached to said parallel rods, transverse link members each pivotally attached to a frame member, and parallel link members pivotally carried by and connecting said transverse link members, a material clamping means, said means including; a pair of jaws carried by each frame, said pair of jaws including a fixed jaw adjacent the side of the material remote from the parallelogram and a movable jaw, resilient means for retracting the movable jaw, and means for in-

termittently engaging the jaws, said means connected to the transverse links and responsive to a pivotal action thereof whereby said jaws clamp the material as the parallelogram is moved in one direction and retract as the direction of movement is reversed, and a timing means for actuating the parallelogram said timing means including; an arm attached to at least one transverse link, a crank having a timed predetermined orbital rotation, and means connecting said arm and crank whereby the timed orbital movement of the crank actuates the parallelogram in a timed reversible movement.

5. A sheet metal feeding apparatus adapted for use with a punch press comprising: articulated link members forming a parallelogram adapted to reciprocally move in the direction of movement of sheet metal; said parallelogram including; axially movable parallel rods, at least two axially spaced clamping frame members transversely attached to said parallel rods, a plurality of transverse link members each pivotally attached to and bodily movable with a frame member, and parallel link members pivotally connected to said transverse link members and adapted to bodily move therewith, a sheet metal gripping means, said means including; a pair of jaws carried by each frame, said pair of jaws including a fixed jaw adjacent the side of the sheet metal remote from the parallelogram and a movable jaw supported by the frame, resilient means for retracting the movable jaw and means for moving the movable jaws, said means operatively connected with the transverse link and responsive to the movement thereof whereby said jaws grip the sheet metal as the parallelogram is moved in one direction and retract as the direction of movement is reversed, and a timing means for actuating the parallelogram said timing means including; an arm attached to at least one transverse link and a mechanism for actuating said arm, said mechanism including; a crank pin connected to said arm and means for causing the axis of the crank pin to move in a path which is substantially a square with rounded corners having two opposite sides thereof parallel to the direction of movement of the sheet metal and two opposite sides at right angles to said direction of movement, said parallel sides having a spacing corresponding to the feeding movement of the sheet metal.
